UNITED STATES PATENT OFFICE.

FRANK W. BACON, OF OMAHA, NEBRASKA.

EXPLOSIVE-ENGINE.

No. 862,377.

Specification of Letters Patent.

Patented Aug. 6, 1907.

Application filed June 15, 1906. Serial No. 321,899.

To all whom it may concern:

Be it known that I, FRANK W. BACON, a citizen of the United States, and a resident of Omaha, in the county of Douglas and State of Nebraska, have invented 5 certain new and useful Improvements in Explosive-Engines, of which the following is a specification.

My invention relates to explosive engines and more particularly to vaporizing and valve mechanism for four cycle engines.

10 It is the object of my invention to provide in engines of the class mentioned a valve mechanism in combination with the inlet and exhaust passages and ports by which the incoming charge of air and oil before entering the cylinders is highly heated by the exhaust gases so that, with the ordinary spraying carburetor, kerosene or heavier fuel oils may be vaporized and used in the engine instead of gasoline or other lighter and more expensive oils.

Constructions embodying my invention are shown in 20 the accompanying drawings in which

Figure 1 is a sectional plan view of a pair of engine cylinders equipped with my vaporizing and valve mechanism, the section being partly on the plane of the lines $x-x$ of Figs. 2 and 3 and partly on the line 25 $y-y$ of said figs.; Fig. 2 is a sectional end elevation of the same, the section being on the plane of the line $z-z$ of Fig. 1; Fig. 3 is a side elevation of the cylinders, partly in section on the line $o-o$ of Fig. 2; Fig. 4 is a detail bottom plan of the cam rod heads for the 30 concentric exhaust and inlet valves; and Fig. 5 is a detail side elevation of the spring-seat for the inlet valve stem.

In the adaptation of my invention illustrated the same is shown as applied to an engine of the vertical 35 multiple-cylinder type having the cylinders cast in pairs and the cylinder heads and valve chambers integral therewith. The cylinders 1 are surrounded by a water space 2 and jacket 3 extending to the lower limit of travel of the piston head, and are bolted on 40 the flat top of a crank housing 4, a portion of which is shown in Figs. 2 and 3. The "half-time" or cam shaft passes longitudinally through the said crank housing and is geared to be driven from the engine crank shaft in the usual manner.

45 Adjacent the bottom of the water jacket 3 the auxiliary exhaust ports 7 connect with the cylinders so that at the lower end of the stroke of the pistons 8 the said ports are uncovered thereby. The said ports 7 extend laterally from the cylinders, as shown in Fig. 1, connecting with the auxiliary exhaust valves 9 which open upwardly into the chambers 10 below the screw plugs 11. The stems 36 of said valves 9 extend downward through the screw-plug guides 37 and at the lower end thereof are provided with spring-seats 38 which are engaged by the springs 39 for holding the valves to their

seats. The chambers 10 connect with a central exhaust chamber 12 as shown in Fig. 3 and at the center and upper part of the casing 18 of said chamber is connected the exhaust pipe 13.

Adjacent the cylinder heads the combustion chambers 6 extend laterally from the cylinders above the exhaust chamber 12, as represented in Fig. 2. From the combustion chambers the cylindrical shells 14 extend downwardly into the exhaust chamber 12 and near the bottom of said shells the passages 15 extend laterally to the outside of the exhaust chamber casing 18. A U-shaped pipe 16 having a side outlet 17 is bolted to the exhaust chamber casing over the outlets of the passages 15, connecting the same as shown. At the upper ends of the shells 14 are formed valve seats 70 on which rest the inlet valve rings 19 which are screwed on the tubular stems 20, said stems extending downwardly through the bottoms of the shells 14, below which ports 21 are formed therein communicating with the exhaust chamber 12.

At the ports 21 the tubular stems are reduced in size and pass out of the exhaust chambers through the screw plugs 22. Above the ports 21 the stems are provided with packing rings 23 which prevent leakage between the exhaust chamber and the annular chambers 24 formed between the shells 14 and the tubular stems 20. At the upper end of the tubular stems 20 are formed valve seats for the exhaust valves 25 of which the stems 26 extend down through the stems 20 and guides 32 therein, as shown. At the lower end of the tubular stems 20 the spring-seats 27 are screwed thereon, the springs 28 encircling the stems between the said seats and the screw plugs 22. The exhaust valve stems extend beyond the end of the tubular stems 20 and have screwed thereon the spring-seats 29, the springs 30 between said seats and the screw plugs 22 being of a diameter large enough to pass over the springs 28 and spring-seats 27. The spring-seats 27 have the fingers 31 extending downwardly therefrom, as shown in Figs. 2 and 5, said fingers passing through openings in the seats 29 and terminating below said seats 29 even with the ends of the exhaust valve stems 26.

The concentric inlet and exhaust valves and also the auxiliary exhaust valves 9 are aligned above the axis of the cam shaft 5 and are operated therefrom as follows: 100 The cam-rod guides 56 are secured on the flat top of the crank housing 4 above the cam shaft by means of the forked retaining bars 33 which are secured to the top of the crank housing by the cap screws 34, the forked ends of said retaining bars resting on the flanges of the guides as shown in Fig. 3. The guides are held against lateral displacement by the dowel pins 35. The auxiliary exhaust valves are actuated by the cams 40 engaging the rollers 41 which are carried by the forked heads 42 on the cam rods 43 which extend up through 105

the guides 56 and engage the valve stems 36, as shown in Fig. 3. The head 42 has guide fingers 44 extending down over the cam shaft as indicated. The inlet valves are operated by the tubular cam rods 45 each of which 5 has on the lower end thereof a forked head 46 having brackets 47 on the sides thereof between which and the main head are carried the rollers 48 which engage the cams 49. The said head 46 has the guide fingers 50 thereon extending down over the cam shaft as shown 10 in Figs. 2 and 3. On the cam shaft between the forks of the head 46 is a cam 51 which is engaged by the roller 52 carried on the head 54 of the cam rod 53 which passes up through the tubular cam rod 45 and engages the end of the exhaust valve stem 26. The head 54 of the cam rod 53 is of cylindrical form and the head 46 is bored out to receive the same, as shown 15 by the bottom plan view thereof, Fig. 4, so that the inner head is guided by the outer. In opening the inlet valves the upper ends of the tubular cam rods 45 engage the ends of the fingers 31 on the spring-seats 29, thereby raising the tubular stems 20 which carry upward therewith the exhaust valves 25 but without 20 permitting the same to open.

Access to the combustion chamber above the concentric exhaust and inlet valves is provided by the screw plugs 55 above said valves, while the chamber 10 above the auxiliary exhaust valves is reached by removal of the screw plugs 11. The cams 40 are so set that the auxiliary exhaust valves 9 will be opened a little before 25 the ports 7 are uncovered by the pistons on the power stroke thereof, and closed after the pistons have covered the ports 7 on the exhaust stroke thereof. During the suction and compression strokes of the pistons said valves 9 remain closed. The cams 51 are set to open 30 the exhaust valves 25 before the ports 7 are covered by the pistons on the exhaust stroke thereof and to close said valves at the end of said strokes. The cams 49 are set to operate the inlet valves during the suction stroke of the pistons.

40 In the operation of the engine a carburetor of any desired form is connected with the outlet 17 of the U pipe 16 connecting with the angular inlet chambers 24. The incoming mixture of air and oil spray from the carburetor in passing through said annular chambers 24 is 45 subjected to an intense heat, as the exhaust gases in their escape pass around the shells 14 and through the tubular stems 20 so that the chambers are heated both from the inside and outside thereof. Baffle plates 57 may be placed on the inner walls of the shells 14, as 50 shown, said plates serving the double purpose of guiding the stems 20 and deflecting the incoming charge of air and oil spray to cause a more perfect circulation

thereof between the heated inner and outer walls of the chambers 24.

Now, having described my invention, what I claim and desire to secure by Letters Patent is:

1. In an explosive engine, an inlet valve having a tubular stem, an exhaust valve positioned within said tubular stem and controlling the passage of exhaust gases through the same, and means for actuating said valves at the proper relative periods.

2. In an explosive engine, an exhaust chamber positioned adjacent the combustion chamber of the engine cylinder, a shell extending from the combustion chamber into said exhaust chamber, an inlet valve having a tubular stem 65 extending through said shell and forming an annular chamber between the same and the shell, said valve controlling communication between the combustion chamber and said annular chamber, a passage connecting with said annular chamber for the admission thereto of combustible materials, and an exhaust valve positioned within the said tubular stem and controlling the escape of exhaust gases through the same into the exhaust chamber.

3. In an explosive engine, an exhaust chamber, a shell extending into said chamber, a valve having a tubular stem 75 extending through said shell and connecting the combustion chamber of the engine with said exhaust chamber, there being an annular chamber formed between said stem and shell and the said valve controlling communication between said annular chamber and the combustion chamber, and a valve positioned within said tubular stem and controlling communication through the same between the combustion chamber and the exhaust chamber.

4. In an explosive engine, concentric exhaust and inlet valves, the inlet valve encircling the exhaust valve and having a tubular stem through which the exhaust passes, a shell inclosing the tubular stem of the inlet valve and forming an annular chamber around the same, an exhaust chamber surrounding said shell, and ports in the tubular stem of the inlet valve connecting the passage through the 80 same with the exhaust chamber.

5. In an explosive engine, concentric exhaust and inlet valves, the inlet valve having a tubular stem through which the exhaust passes, a shell surrounding said stem, an exhaust chamber around said shell, ports connecting 85 the passage through said stem with the exhaust chamber, an auxiliary exhaust port adapted to be opened by the engine piston at one end of its stroke, and passages connecting said port and the exhaust chamber.

6. In an explosive engine, an exhaust chamber, a port 100 in the engine cylinder adapted to be uncovered by the piston at one end of the stroke thereof, a valve-controlled passage connecting said port and the exhaust chamber, a shell disposed within said exhaust chamber, an inlet chamber within said shell having valved connection with the engine cylinder combustion chamber, a tubular stem passing through said inlet chamber, and means for passing a portion of the exhaust gases through said tubular stem.

In testimony whereof I have hereunto subscribed my name in the presence of two witnesses.

FRANK W. BACON.
